SIDE DELIVERY AUTOGRAPHIC REGISTER

Louis Jensen, Chicago, Ill., assignor to United Autographic Register Co., Chicago, Ill., a corporation of Illinois

Application February 24, 1936, Serial No. 65,482

4 Claims. (Cl. 282—16)

This invention relates to autographic registers and more particularly to an improved feeding and aligning device for an autographic register of the side delivery type.

5 The primary object of the invention is to provide an improved feeding and aligning device in an autographic register having a supply-compartment and a record-compartment in which is filed a record slip having original entries thereon while carbon copies are issued from an opening in the side wall of the machine.

In machines of this character a lateral delivery chute is usually disposed between the two compartments and the feeding device is usually 15 disposed above the chute. Accordingly, it will be understood that any satisfactory feeding device must not occupy much head room or the machine will be unduly high.

Heretofore, side delivery registers have been 20 provided, as exemplified by my Patent No. 1,873,593, issued August 23, 1932, with feed mechanism having narrow feed disks in alignment with the register perforations in the stationery, and alignment was accomplished by loss of traction on the strips when the perforations reached 25 the grip of the rolls. With that type of feed device, special restarting mechanism was required and difficulty was encountered in initially loading the machines, unless special register pins were provided for that purpose. In the 30 present invention the feed-rolls operate independently of any register perforations and the aligning means which include jogging fingers serves to position the stationery properly during 35 the loading operation.

The invention is illustrated in the preferred embodiment in the accompanying drawings, in which—

Figure 1 is a broken perspective view of an 40 open side delivery autographic register embodying the invention; Fig. 2, a broken longitudinal sectional view of the feeding and aligning mechanism, taken as indicated at line 2 of Fig. 1; Fig. 3, a view similar to Fig. 2, but showing 45 the mechanism in a different position; Fig. 4, a broken transverse sectional view taken as indicated at line 4 of Fig. 2; Fig. 5, a broken longitudinal sectional view taken as indicated at line 5 of Fig. 4; and Fig. 6, a perspective view of 50 one of the slotted channel members which carries a jogging finger.

In the embodiment illustrated, A designates a register casing provided with a platen A', a supply-compartment A², a record-compartment 55 A³, and a lateral delivery chute A⁴; B, feed

mechanism having an upper feed roll mounted in a housing B'; and C, aligning mechanism.

The casing A is practically identically shown in my Patent No. 1,873,593, and has its platen A' hinged to one side of the register so that it may be raised to permit access to the supply-compartment A². The rear of the platen may be provided with a suitable guide mechanism or tension device 7 over which stationery strips 8 may be drawn from a zigzag folded packet in 10 the supply-compartment. The platen and tension device is ordinarily enclosed by a skeleton cover 9 which is hinged to one side wall of the casing as indicated at 10 and is provided with a latch 11. Preferably the record-compartment 15 A³ is provided with a hinged cover 12 which may be locked in closed position by a suitable lock 13. The lateral delivery chute A⁴ is disposed beneath the feed mechanism B and is shaped somewhat like a "cornucopia" so that an 20 underlying stationery strip projected therethrough by means of a feed mechanism will be projected out through a side wall of the casing and will be understood from my above patent.

As best shown in Figures 2-5, inclusive, the 25 feed mechanism B comprises a lower feed roll 14 which is journaled in the side walls of the casing and is provided with the central feed drum 15. As shown in Figures 4 and 5, the feed roll is provided at one end with a spur 30 gear 16 which meshes with an idler gear 17 which, in turn, meshes with a driving cam gear 18 which is mounted on a crank shaft 19. As shown in Fig. 1, the crank shaft is provided with a crank 20 which is automatically engaged by 35 locking mechanism 21 so that rotation of the crank will be stopped automatically after each complete revolution. The locking mechanism is similar to that shown in my above patent and need not be described in detail.

An upper feed roll shaft 22 is journaled in the housing B' which is pivoted to the casing at 23. The journal members in the housing are slotted and provided with springs 24 to yieldingly urge feed drums 25 into contact with stationery resting on the drum 15 when the housing is held in a position shown in Fig. 4 by means of a releasable catch 26. The lower feed roll shaft 14 is provided at one end with a spur gear 27 which meshes with the spur gear 28 fixed 45 to the upper feed roll shaft 22. The gears are matched so that the drums 15 and 25 will rotate in opposite directions with the same peripheral speed.

The upper feed roll shaft 22 extends laterally 50 55

from the housing B' and is adapted to be raised from contact with the stationery by means of a bell crank lever 29 which is pivotally mounted on the casing at 30 . The lower end of the crank 29 is provided with a roller 31 which rides upon a cam 32 and thereby causes the stationery feeding to be arrested momentarily during each revolution of the shaft 19 .

The aligning mechanism, which also serves to complete the last portion of the advance of a form length before the crank 20 becomes locked, is shown with channel-like members 33 slidably supported on capped studs 34 provided on cross plate 35 which is secured to the side walls of the machine. The edge portions of the channel members are provided with slots 36 which are adapted to be engaged by upwardly extending arms 37 provided on a rock shaft 38 . Within the casing, one end of the shaft is provided with an operating arm 39 provided with an outwardly extending stud 40 projecting through a slot 41 in the casing, into engagement with a cam 42 fixed to a cam gear 43 which is pivotally mounted on the casing at 44 and is driven by the idler gear 17 . The arm 39 has an upward extension 45 to which is connected a tension spring 46 which urges the stud 40 into engagement with the cam 42 . Thus it will be understood that rotation of the cam gear 43 will cause the slide member 33 to be reciprocated in timed relation to the movement of the feed mechanism. The front end portions of the channel members 33 are provided with jogging fingers 47 which are urged upwardly into engagement with register perforations by means of tension springs 48 which are connected to downward extensions 49 of the slide members 33 .

When the crank is in the locked position shown in Fig. 1, the jogging fingers 47 are in the position shown in Fig. 3 and facilitate proper loading of the stationery. After a set of forms has been filled in, the crank 20 is given one complete revolution. This action will cause the slide members 33 to be drawn rearwardly by the arms 37 and the stationery will be advanced slightly less than a form length by feed drums 15 and 25 . At this point the bell crank 29 will raise the upper feed roll shaft 22 and the jogging fingers will be projected forwardly from the position shown in Fig. 2 to the position shown in Fig. 3. This action will permit the fingers to engage perforations in the stationery and complete the advance of the form to a registered writing position. The top or original form will be projected into the compartment A^3 and the carbon copy will be projected into the delivery chute A^4 where it may be severed on its line of weakening by drawing the same against a tear-off edge 50 shown in Fig. 3.

To load the machine initially the cover 9 and the platen A' are swung upwardly and a zigzag folded packet of stationery is placed in the supply-compartment A^2 . Strips of stationery 8 are then draped around the tensioning or guiding mechanism 7 over the platen A' , in interleaved relation with carbon strips 51 , and impaled by jogging fingers 47 which are in the position indicated in Figs. 1 and 3. The housing member B' may then be latched in the position shown in Fig. 4 and after the skeleton cover 9 is closed the machine is ready for use. If desired, more than one

strip may be projected into the chute by initially placing their ends beneath a divider bar 52 , or, if desired, additional copies may be projected into the record-compartment by starting them over the divider bar 52 , as will be readily understood. 5

The foregoing detailed description is given for clearness of understanding only, and no unnecessary limitations should be understood therefrom, but the appended claims should be construed as broadly as permissible in view of the prior art. 10

I claim:

1. An autographic register comprising: a casing provided with a platen, a supply-compartment, a record-compartment, and a laterally open delivery chute between said compartments; feeding mechanism in said casing above said chute for projecting an upper strip into the record-compartment and a lower strip through the chute comprising a lower feed roll, an upper feed roll 20 yieldingly urged towards the lower feed roll by means of a spring, means for driving said lower feed roll and periodically lifting said upper feed roll so as to advance the strips less than a form-length; and longitudinally reciprocal aligning 25 means having fingers adapted to engage perforations in the stationery and move forwardly to advance and project the lower strip through said laterally open delivery chute.

2. A device as specified in claim 1, in which the driving means comprises a crank shaft geared to the lower feed roll, said shaft being equipped with cam-means for actuating a bell crank adapted to raise one end of the upper feed roll against the pressure of the spring. 30

3. A device as specified in claim 1, in which a cam-gear is provided to operate the aligning means, a crank shaft is also provided with a cam-gear for raising one end of the upper feed roll against the pressure of the spring, the lower feed 40 roll is provided with a driving gear, and an idler gear is provided in mesh with both of said cam-gears and driving gear so that all will be operated in timed relation.

4. An autographic register comprising: a casing provided with a platen, a supply-compartment, a record-compartment, and a laterally open delivery chute between said compartments; feeding mechanism in said casing above said chute for projecting an upper strip into the record-compartment and a lower strip through the chute comprising a lower feed roll, an upper feed roll yieldingly urged towards the lower feed roll by means of a spring, means for driving said lower feed roll and periodically lifting said upper feed roll against the pressure of the spring so as to advance the strips less than a form-length; and aligning means comprising a pair of jogging fingers pivotally mounted in slotted channel members slidably mounted beneath said platen, a rock shaft having upwardly extending arms adapted to engage the slots in said channel members to reciprocate same, and cam-means for rocking said shaft forwardly when the upper feed roll is raised so that the fingers engage perforations in the strips to align and complete the feed a form-length and project the lower strip through said underlying chute. 55

LOUIS JENSEN.
